UNITED STATES PATENT OFFICE.

THOMAS J. STEINKELLER, OF EUREKA, CALIFORNIA.

BLEEDER VALVE FOR AIR-BRAKE SYSTEMS.

1,409,605.

Specification of Letters Patent. Patented Mar. 14, 1922.

Application filed February 18, 1920. Serial No. 359,739.

To all whom it may concern:

Be it known that I, THOMAS J. STEINKELLER, a citizen of the United States, residing at Eureka, in the county of Humboldt and State of California, have invented new and useful Improvements in Bleeder Valves for Air-Brake Systems, of which the following is a specification.

This invention relates to an improved bleed valve for exhausting the air from the air brake apparatus on a railway car in order to release the air brakes on said car.

When a train of cars is hauled into a terminal or freight yard to have the various cars of the train distributed to certain points of the yard or terminal, particularly in the case of freight cars, upon uncoupling the engine from the cars the brakes will immediately set. To now haul the cars to designated points in the yard to to provide for "kicking" the cars onto sidings with a switch engine, it is necessary that some member of the train or yard crew open the bleeder valve in each car to release the air brakes. This requires that the operator hold the bleeder valves open until the air is exhausted from the auxiliary reservoirs and much time and labor is expended in thus bleeding a train of cars. The ordinary yard or switch engine does not have its air system coupled with the train line of the air brake system of the train of cars and for this reason the aforementioned bleeding of the air lines is necessary to release the brake.

It is the primary object of my invention to provide an improved bleeder valve which will operate so as to consummate a great saving in time and labor such as required at the present time to bleed the cars of a train. To this end, I provide a valve, which when opened by the operator will remain open, and allow the air in the air brake apparatus to exhaust without necessitating that the operator hold the valve in open position.

Another object of the invention is to provide a bleeder valve of the character described, which after being opened will automatically close immediately upon the connection of the train line of the car to which it is attached, with the air supply apparatus of a locomotive.

The invention possesses other advantages and features, some of which, with the foregoing will be set forth at length in the fol-

lowing description wherein I shall outline in full that form of the invention which I have selected for illustration in the drawings accompanying and forming a part of the present specification. I said drawings I have shown one form of the construction of my invention but it is to be understood that I do not limit myself to such form, since the invention as expressed in the claims may be embodied in a plurality of forms.

Referring to the drawings: Figure 1 is a side elevation of the bleeder valve of my invention showing it screwed into the upper side of the auxiliary air tank, part of the latter of which being shown in section.

Figure 2 is a vertical sectional view of the valve of my invention showing it as it appears when closed.

Figure 3 is a vertical sectional view of the valve showing it as it appears when open.

Figure 4 is a sectional view taken on the line 4—4 of figure 2.

Figure 5 is a sectional view taken on the line 5—5 of figure 3.

Figure 6 is a diagrammatic view showing a part of the air brake apparatus of a railway car and the valve of my invention mounted on the auxiliary air reservoir.

In carrying out my invention, I provide a bleed port in communication with the air brake apparatus of a railroad car and control said port by a valve, which valve when moved to open the port will, without being manually held, remain in open position and allow air to exhaust from the apparatus into the atmosphere, whereby the brakes of the car will be released. In connection with the valve I provide closing means therefor operated by air pressure and I connect this means with the train line of the apparatus so that when the car train line is connected with a locomotive, air supplied to the car train line will automatically actuate this closing means, close the valve and allow the auxiliary reservoir to fill without "bleeding."

Referring to the drawings, 1 designates the train line of the air brake apparatus of a railroad car, connected by a pipe 2 with the usual triple valve 3. The triple valve is operatively associated with the auxiliary reservoir 4 and brake cylinder 5 in the usual manner. This apparatus is of the type generally employed as part of the present day

air brake equipment for railroad cars and need not be illustrated and described in detail.

I preferably mount the bleed valve 6 of 5 my invention on the auxiliary reservoir 4 but I may otherwise connect this valve with the apparatus if desired. Valve operating handles 7 and 8 extend from the valve to opposite sides of the car (not shown) so 10 that the valve may be operated from either side of the car.

The valve of my invention preferably comprises a casing 9 having one end open and externally screw threaded as at 10 and its 15 other end closed as at 11, the open threaded end being turned in a screw threaded opening 12 in the auxiliary reservoir 4. A bleed port 13 is formed in the side of the casing and communicates with the atmosphere and 20 the interior of said casing. A valve seat 14 is secured in the casing over the port and has an opening 15 therein registering with said port. A valve 16 is slidably mounted on the valve seat and operates to open and 25 close the bleed port. A plunger or stem 17 is mounted to reciprocate through a stuffing box 18 in the closed end of the casing and the valve is connected with and operated by the plunger. The packing in the stuffing 30 box not only prevents leakage between the valve and piston chambers, but also frictionally retains the stem in the upper position when the valve is closed by the rising piston, thus helping to avoid the undesired 35 opening of the valve and the premature bleeding of the brakes when the train line pressure falls to that of the atmosphere. The casing 9 is provided with an intermediate lateral enlargement 19 having angularly disposed, flat, wrench-engaging faces 20. The closed end of the casing is externally screw threaded and is turned into the open threaded end 21 of a cylinder 22. This 40 end of said cylinder rests upon the enlargement 19. The plunger or stem 17 extends into this cylinder and has a piston 23 thereon mounted intermediate of its ends, said piston having a working fit in said cylinder. The plunger extends through the closed end 45 24 of said cylinder and terminates between spaced ears 25 on said end. Pivoted to the ears 25 are bell cranks 26 and 27. The short arm 28 of the bell crank 26 rests upon the outer end of the stem 17 whereas the shorter 50 arm 29 of the bell crank 27 rests upon the outer end of the arm 28. By pulling outwardly on the lower end of either bell crank, the plunger is depressed and moves to open 55 the valve 16. The handles 7 and 8 are connected with the lower ends of the bell cranks and provide for operation of the valve from either side of a car.

The valve 16 is preferably mounted upon the plunger 17 by being supported upon a 60 bolt 30 which is turned in a threaded open-

ing 31 in the inner end of the plunger. This bolt is reduced as at 32 to provide annular shoulders 33 engaged by ears 34 on the valve. The ears embrace the reduced portion of the bolt between the shoulders. A pin 35 is 70 inserted through the outer ends of the ears and supports a bowed leaf spring 36 which latter slidably engages upon the wall of the valve casing so as to yieldingly force the valve 16 towards its seat to provide a tight 75 working engagement between the parts. This valve is of course also held to its seat by the pressure of the air thereon. By thus mounting the valve, I may easily disassemble the valve without disassembling the entire 80 device.

A by-pass pipe 37 is connected with the train line 1 and with a port 38 in the cylinder 22 so as to supply air to the cylinder to 85 operate the piston and close the valve 16.

To operate my valve, one of the handles 7 and 29 is pulled outwardly and the plunger 17, assuming that the valve is closed, will be depressed by one of the bell cranks 26 and 27. When the plunger 17 is 90 depressed, the valve 16 will be moved from closed position as shown in Figure 2, to the open position shown in Figure 3 and the air in the auxiliary reservoir 4 will escape through the casing 9 and bleed port 13 and 95 release the brakes (not shown). The valve will remain open when once opened and all that is needed to bleed the reservoir is to give a pull upon one of the operating handles 7 and 8.

Whenever air is admitted to the train line, air will pass into the pipe 37 and enter the cylinder 22 behind the piston 23, causing the piston to move outwardly and likewise move the plunger 17 so that the valve will 100 be closed. Thus the valve will automatically close when the train line is coupled with the train line of a train or engine. With the valve closed the apparatus is 105 restored to operative condition by the filling 110 of the auxiliary reservoir through the triple valve.

In the weighing of freight cars it is required that all of the air be exhausted from the braking apparatus of each car prior 115 to the weighing thereof. This requires with the apparatus now in use, that the bleed valves be held open until the air is exhausted. With my valve wherein it is only necessary to open the valve and not to 120 hold the same open, I secure a great saving in time and labor in the weighing of cars.

Railway cars which have completed a run and have been uncoupled from the locomotive must be inspected before being again 125 put into use. In the inspection of these cars, it is necessary after inspection to bleed the air apparatus and where a train of cars must be thus bled, much time and labor is required to hold the bleed valves open in 130

the several cars. In my valve, since it is only necessary to move the valve open in order to bleed the cars, much time and labor will be saved in the inspection of the cars 5 as aforementioned.

I claim:

1. A bleed valve for air brake apparatus comprising a housing formed with a piston chamber in communication with the train 10 line and with a passage for connecting the auxiliary reservoir with the open air, a valve for controlling the flow of air through said passage, a piston slidably arranged in said chamber, a stem connecting said piston and 15 said valve, and manually operated means for moving said valve.

2. A bleed valve for air brake apparatus comprising a housing formed with a piston chamber in communication with the train 20 line and with a valve chamber opening into the auxiliary reservoir and a passage from the valve chamber to the open air, a valve for controlling the flow of air through said passage, a piston slidably arranged in the 25 piston chamber, a stem connecting said piston and said valve, and manually operated means for moving said valve.

3. A bleed valve for air brake apparatus comprising a housing formed with a passage for connecting the auxiliary reservoir with the open air, a valve for controlling the flow of air through said passage and pressed upon its seat by air from the auxiliary reservoir, and means operated by 35 air from the train line for closing said valve.

4. A bleed valve for air brake apparatus comprising a housing formed with a passage for connecting the auxiliary reservoir with the open air, a valve for controlling the flow 40 of air through said passage and pressed upon its seat by air from the auxiliary reservoir, an operating stem for said valve slidably arranged in said housing, means for packing said stem in said housing, manually operated 45 means for moving said stem in one direction to open said valve, and means operated by air from the train line for closing said valve.

5. A bleed valve for air brake apparatus comprising a housing formed with a passage for connecting the auxiliary reservoir with the open air, a valve for controlling the flow of air through said passage and pressed upon its seat by air from the auxiliary reservoir, 55 an operating stem for said valve slidably arranged in said housing, means for packing said stem in said housing, manually operated means for moving said stem in one direction to open said valve, a piston on said 60 stem, and means for permitting air from the train line to actuate said piston to close said valve.

6. A bleed valve for air brake apparatus comprising a housing formed with a piston 65 chamber in communication with the train

line and with a passage for connecting the auxiliary reservoir with the open air, a valve for controlling the flow of air through said passage and pressed upon its seat by air from the auxiliary reservoir, a piston slidably arranged in said piston chamber, and means for connecting said valve to said piston.

7. A bleed valve for air brake apparatus comprising a housing formed with a piston 75 chamber in communication with the train line and with a passage for connecting the auxiliary reservoir with the open air, a valve for controlling the flow of air through said passage and pressed upon its seat by air 80 from the auxiliary reservoir, a piston slidably arranged in said piston chamber, means for connecting said piston to said valve, and manually operated means for moving said valve in one direction.

8. A bleed valve for air brake apparatus comprising a housing formed with a piston chamber in communication with the train line and with a passage for connecting the auxiliary reservoir with the open air, a valve 90 for controlling the flow of air through said passage and pressed upon its seat by air from the auxiliary reservoir, a piston slidably arranged in said piston chamber, a stem connecting said piston to said valve and extending exteriorly of said housing, and manually operated means for moving said stem to open said valve.

9. A bleed valve for air brake apparatus comprising a housing formed with a piston 100 chamber in communication with the train line and with a passage for connecting the auxiliary reservoir with the open air, a valve for controlling the flow of air through said passage and pressed upon its seat by air from 105 the auxiliary reservoir, a piston slidably arranged in said piston chamber, a stem connecting said piston to said valve and extending exteriorly of said housing, a lever engaging the end of said stem, and means for moving said lever to effect the opening of said valve.

10. A bleed valve for air brake apparatus comprising a housing formed with a piston chamber in communication with the train 115 line and a passage for connecting the auxiliary reservoir with the open air, a stem slidably mounted in said housing, a piston in said piston chamber fixed on said stem for co-extensive axial movement therewith, a 120 valve for controlling the flow of air through said passage connected to said stem, and means for moving said stem to open said valve.

11. A bleed valve for air brake apparatus 125 comprising a housing formed with a piston chamber in communication with the train line and a passage for connecting the auxiliary reservoir with the open air, a stem slidably mounted in said housing, a piston 130

in said piston chamber fixed on said stem for co-extensive axial movement therewith, a valve for controlling the flow of air through said passage connected to said stem, means 5 for moving said stem to open said valve, and means for lightly resisting the movement of said stem.

12. A bleed valve for air brake apparatus comprising a housing enclosing a valve chamber and attachable to the auxiliary reservoir 10 with said chamber in communication there-

with, said housing being formed with a passage for connecting said chamber with the open air and with a piston chamber in communication with the train line, a stem disposed in said chambers, means for packing the stem between the chambers, a valve in said valve chamber and a piston in said piston chamber connected to said stem and manually operated means for moving the stem in one 15 direction.

THOMAS J. STEINKELLER.
